UNITED STATES PATENT OFFICE.

ROBERT S. CURLEY AND JOSEPH MOSS, OF NEWTON, MASSACHUSETTS, ASSIGNEES TO SACO-LOWELL SHOPS, OF BOSTON, MASSACHUSETTS, A CORPORATION OF MASSACHUSETTS.

EVENER.

1,102,726.

Specification of Letters Patent.

Patented July 7, 1914.

Application filed July 3, 1913. Serial No. 777,361.

To all whom it may concern:

Be it known that we, ROBERT S. CURLEY and JOSEPH Moss, of Newton, in the county of Middlesex and State of Massachusetts, have invented a new and useful Improvement in Eveners, of which the following is a specification.

Our invention relates to an improvement in eveners or the like whereby the pedals are made much shorter and more compact than is usual, their mounting and connection with the belt shifting mechanism are simplified, and the pressures counterbalanced so that there is a resulting decrease of strain upon the machine and consequently lighter construction may be used.

Our invention will be understood by reference to the drawings, in which it is shown embodied in the preferred manner.

Figure 1 is a front elevation of the mechanism referred to and Fig. 2 an end elevation, the shafts, etc., in each case being in section.

Only so much of the machine is shown as is necessary to illustrate the arrangement to be described.

A is a portion of the frame. A¹ is the beater and B, B the feed rolls, all of which together with the ticing roll C are operated in the usual manner.

A², A³ are supports adjustably mounted on top of the frame A and connected by the girt D. In these supports the feed rolls B, B and ticing roll C are mounted, this construction being such that these parts and other parts supported therefrom may be adjusted bodily toward and from the beater A¹. The girt D is preferably narrowed or beveled on its upper edge as shown to form a fulcrum for the pedals. The girt is also slotted as at d to provide a bearing surface or fulcrum for the rear end of the shipping lever J.

The pedals E are constructed as short plates, and extend across the machine, and are of convenient number and width. Each plate rests upon the upper edge of the girt D and is provided with means such as the notch e to hold it in place on the girt so that preferably one end will be longer than the other, the longer end extending under the ticing roll C. The other end of each plate has a flange e¹ which extends downwardly from it and is perforated as at e². From each perforation hangs a link e³

which is preferably open as shown in Fig. 2 so as to be easily removed from the pedal if desired.

F, F are yokes which connect links e³, e³. G, G are yokes which connect links f, f one of which is suspended from each yoke F. H is a still longer yoke which is suspended from links g which hang from the yokes G. The number of links and yokes will of course depend in any case upon the number of plates used. This construction does away with the rearwardly-extending long arms usual in this type of machine and makes a compact mechanism which simplifies construction materially.

J is a lever one end of which rests against the under side of the girt D. The other end of the lever J is hook-shaped to receive the eye h in the upper end of the connecting rod K. Intermediate the ends of the lever J it is notched as at j to rest upon the yoke H. The lower end of the connecting rod K is connected to an arm l on a shaft L at the other end of which is a slotted upright arm l¹, the whole forming a bell-crank mechanism. The arm l¹ is connected by a second connecting rod m² with an arm m¹ on a shaft m mounted in the frame A. The shaft m also carries a segment gear M which engages a rack M¹ mounted to slide longitudinally and carrying a belt shifter indicated at M² by which the belt N is moved along the cone pulleys N¹ to change the speed of the rolls as occasion may require. It will be noted that in this construction the girt serves as a support for the plates and that the strain upon it is counterbalanced because it also serves as a fulcrum for the lever J which presses on its under side. As a result this support may be made quite light.

The operation of this mechanism and its possibilities will be easily understood. As the lap is drawn along by the feed rolls it passes over the plates and under the ticing roll at a normal speed. When any bunch or undue thickening of the lap reaches the ticing roll it tends to depress the free long end of the plate, thus raising the long arm of the lever J and by means of the connections between it and the segment gear M, moving the segment gear and by means of the rack M¹ shifting the position of the belt N on the cone pulleys N¹ and thus slowing down the speed of the feed rolls B, B so

that they can take care of the lap and deliver it in a uniform condition.

Our invention is a simple solution of a problem. It takes but little room on the machine; in fact, it is very economical of space compared with other mechanisms used for the purpose, and has proved very practicable. In details of construction it may of course be altered without departing from its essentials, an important feature of it being the mounting of the plates on the girt as a fulcrum and the use of the under side of the same girt as a fulcrum for the lever so that these pressures support each other and to a considerable extent neutralize the strain upon the girt, at the same time providing a firm bearing for each part. The plates are short and they are connected by simple connections with the lever so as to get most efficient results with a few number of parts. The individual plates may be removed separately for repair or otherwise, if desired, with but little trouble.

What we claim as our invention is:—

1. In a machine of the kind described, an evener mechanism comprising a girt, a series of plates mounted thereon, a ticing roll mounted above said plates, cone pulleys, a belt shifter therefor, and means comprising a lever one end of which is connected to said belt shifter, the other end engaging said girt and intermediate connections connecting said lever with said plates whereby said plates may cause the operation of said belt shifter.

2. In a machine of the kind described, a feed mechanism and an evener mechanism comprising a girt, a series of plates mounted thereon, a ticing roll mounted above said plates, a belt shifter and connections between said belt shifter and said plates comprising a lever one end of which is fulcrumed on the under side of said girt, means for connecting the other end of said lever with said belt shifter and connections intermediate the two ends of said lever connecting said lever and said plates whereby the movement of said

plates will cause the operation of the belt shifter and the changing of the speed of the feed.

3. In a machine of the kind described, a feed mechanism and an evener mechanism comprising a ticing roll, plates located thereunder, means for supporting said plates comprising a girt and means for balancing said plates on said girt comprising a lever one end of which engages the under side of said girt, means for connecting the other end of said lever to a belt shifter and means engaging the lever between its ends for connecting said lever with said plates, whereby upon the depressing of the ends of the plates under the ticing roll said lever will be lifted and the belt shifter operated.

4. In an evener mechanism, a pedal having an integral downwardly-projecting flange upon its rear end, its other end being adapted to lie under a ticing roll, said pedal having on its under side means to hold it in place upon a support.

5. In a machine of the kind described, an evener mechanism comprising a girt, a plurality of short plates fulcrumed upon the girt, a ticing roll coöperating with the plates upon one side of their fulcrums, a reducing motion connected directly with the plates upon the other side of their fulcrums, and a belt shifter mechanism operated by the reducing motion.

6. In a machine of the kind described, a girt, a ticing roll, a plurality of plates fulcrumed upon the girt, each plate coöperating with the ticing roll upon one side of its fulcrum and having an integral perforated flange upon the other side of its fulcrum, a belt shifter mechanism, and connections between the perforated flanges and the belt shifter mechanism.

ROBERT S. CURLEY.
JOSEPH MOSS.
